UNITED STATES PATENT OFFICE

EDWIN H. ALLFREE, OF IRONTON, OHIO

CONVEYER

Application filed April 16, 1930. Serial No. 444,723.

My present invention relates to conveyers of the reciprocating pan or chute type, such as shown and described in United States Letters Patent, No. 1,662,808, granted to myself and Albert R. Williams, on March 20, 1928.

This invention relates particularly to corner pans or chutes (hereinafter referred to, for convenience, simply as "pans"), such as may be used at a point where the train of pans is laid around a corner or otherwise changes its direction.

The objects of this invention are as follows:

First, to construct a corner pan in such manner that there will be no retardation of flow of the coal, ore, or other material being conveyed.

Second, to construct a corner pan in such manner that its operation, in the train, will be free from binding effect or undue friction, and will require the use of no excess of power.

Third, to construct a corner pan in such manner that it may be quickly and easily connected to, or disconnected from, the straight pans which flank it, in the train.

Fourth, to construct a corner pan in such manner that it may be quickly and easily adapted for use in connection with either a right hand or left hand turn of the train.

Fifth, other objects and advantages of the invention will manifest themselves from the detailed description to follow, and will be pointed out in the appended claims.

These objects are attained in the manner hereinafter set forth, reference being had to the accompanying three sheets of drawings, in which:

Figure 1 is a top plan view of a corner pan constructed in accordance with this invention, together with parts of the two flanking straight pans, and illustrates the manner in which they are secured in operative connection;

Figure 2 is a projected longitudinal vertical sectional view on the partly straight and partly arcuate line 2—2 of Figure 1;

Figure 3 is a transverse vertical sectional view on the line 3—3 of Figure 1;

Figure 4 is a similar view on the line 4—4 of Figure 1;

Figure 5 is a similar view on the line 5—5 of Figure 1; and,

Figure 6 is a diagrammatic top plan view of a series of pans in a train, and illustrates the manner in which corner pans, constructed in accordance with this invention, are adapted for use in such a train.

Referring, in the first instance, to Figure 1 of the drawings, there is shown a corner pan A having its receiving end in operative connection with the delivery end of a straight pan B, which precedes it in the train, and having its delivery end in similar connection with the receiving end of a similar straight pan C, which follows it therein.

The corner pan A is of substantially arcuate form and embodies a bottom 10 and side walls 11. At its receiving end this pan is connected, by means of a swivel joint x, to the delivery end of the straight pan B, and, at its delivery end, it is similarly connected, by means of another swivel joint y, to the receiving end of the straight pan C.

The swivel joint x comprises, as best shown in Figure 5, a male member 12 carried by a swivel plate 13 fixedly secured to the pan B, and a female member 14 fixedly secured to a saddle 15, which is screwed, bolted, or otherwise removably secured to the corner pan A. The male and female members are maintained in operative engagement with each other by means of a nut or bolt connection. The bolt 16 is provided with a spherical head 17 and the nut 18 is secured in place by means of a locking pin 19. Sufficient play is allowed to permit free action of the swivel.

The joint y is of substantially identical construction, except that the male member is carried by the saddle removably secured to the corner pan A and the female member is carried by the swivel plate of the pan C.

Inasmuch as the swivel carrying saddles are readily removable from the pan A, they may be quickly and easily changed, end for end, on such pan, and the pan thus easily adapted for either a right hand or a left hand turn.

The pan A is mounted upon and carried by a frame consisting of a pair of radial arms 20 projecting from a ball and socket mount-

ing 21 which is positioned at the center about which the arc of the pan A is cast. The outer ends of the arms 20 are fixedly secured to plates 22 mounted upon the bottom of the pan A and they are provided with a cross brace 23.

The pan A has a wheeled mounting consisting of a wheel 24 adapted to roll back and forth upon a track 25, and mounted upon an axle 26, one end of which is guided between a track 27 secured to the pan A, and the other end of which rotates between pins 28 upstanding from the brace bar 23. When the swivel carrying saddles are reversed, end for end, on the pan to change it from a left hand turn, as illustrated, to a right hand turn, the wheel 24 is removed and similarly mounted adjacent the other end of the pan, its axle, then, engaging a similar track 27^a, reversed and secured to bottom of pan, and the pins 28 on the bar 23.

The manner in which the train of pans is horizontally reciprocated, and the means employed for imparting reciprocating movement thereto is fully illustrated and described in the patent of Allfree and Williams, hereinbefore mentioned, or any one of the several different kinds of drive mechanism used for this type of conveyer. This feature forms no part of the present invention and is, consequently, not shown nor dwelt upon herein.

In Figure 6 there is illustrated a train of pans in which are included both right hand and left hand turn corner pans, these pans being shown of both 90° turn and 45° turn.

While the corner pans illustrated are shown as of arcuate form, this is not always essential. In the case of certain turns in the train, especially those of but slight degree, a corner pan having a straight center line may be efficiently employed provided its mounting and connections are as shown and described. In other words, the important feature is that the corner pan must move, when the conveyer is in operation, in an arcuate path about its fixed pivotal mounting.

Quite obviously many other changes may be made in the form, shape and general structure of a corner pan, and, also, in its mounting and connection means, without any departure from the spirit of this invention, provided such modifications fall within the scope of the appended claims.

What is claimed is:

- 65 1. A corner pan for a horizontal reciprocable conveyer train, said pan being formed with an arcuate center line.
2. A corner pan for a horizontally reciprocable conveyer train, said pan being formed with an arcuate center line, and a mounting frame for said pan, said frame having a pivotal mounting at the center about which the arc of the pan is cast.
- 65 3. An arcuate corner pan for a horizontally

reciprocable conveyer train, a female member of a swivel joint mounted at one end thereof, and a male member of a swivel joint mounted at the other end thereof, said members being adapted to engage with complementary members carried by adjacent pans in the train. 70

4. The elements as set forth in claim 3, but with the said members of swivel joints removably mounted upon the said corner pan. 75

5. An arcuate corner pan for a horizontally reciprocable conveyer train, a pair of saddles mounted one at each end thereof, and swivel joint members carried by said saddles, a female member by one saddle and a male member by the other. 80

6. The elements as set forth in claim 5, but with the said saddles removably mounted upon the said pan.

7. An arcuate corner pan for a conveyer 85 train, a pivotal mounting therefor at the center about which the arc is cast, and a wheeled support therefor.

8. The elements as set forth in claim 7, but with the said wheeled support capable of longitudinal adjustment upon the said pan. 90

9. A corner pan for a conveyer train and a laterally spaced pivotal mounting therefor, whereby any movement of the pan will be in an arcuate path about the pivotal mounting. 95

10. A corner pan for a conveyer train, a mounting frame for said pan, said frame extending laterally from said pan, and a pivotal mounting for the lateral extension of said frame, whereby any movement of the pan will be in an arcuate path about the pivotal mounting. 100

11. A corner pan for a conveyer train, said pan having a receiving end and a discharge end, and a mounting therefor, whereby any movement of the said ends will be in arcuate paths about a common center. 105

12. A corner pan for a horizontally reciprocable conveyer train, said pan being formed with an arcuate center line and having a receiving end and a discharge end, a pivotal mounting therefor at the center about which the arc is cast, whereby any movement of the said ends will be in arcuate paths about a common center, and shiftable means co-operating with the underside of said mounting for interchanging said receiving end and discharge end. 110

In testimony whereof, I hereunto affix my signature.

EDWIN H. ALLFREE.
